UNITED STATES PATENT OFFICE.

THOMAS L. GREGSON AND JAMES I. PAYETTE, OF CHICAGO, ILLINOIS.

WIRE-STRIPPER.

1,065,679.

Specification of Letters Patent. Patented June 24, 1913.

Application filed May 2, 1910. Serial No. 559,020.

To all whom it may concern:

Be it known that we, THOMAS L. GREGSON and JAMES I. PAYETTE, citizens of the United States, residing at Chicago, in the county of Cook and State of Illinois, have invented a certain new and useful Improvement in Wire-Strippers, of which the following is a specification.

Our invention relates to improvements in wire strippers, and has for its object to provide a new and improved apparatus for the stripping of both duplex and single wires. It is illustrated in the accompanying drawings, wherein—

15 Figure 1 is an end elevation. Fig. 2, a section along the line 4—4 of Fig. 1; Fig. 3, a section along the line 5—5 of Fig. 1.

Like parts are indicated by like letters throughout the several figures.

20 The handles A, A¹, are provided with the inwardly extending lugs C upon which the jaws C¹, C², are held by means of the rivets C³. The jaws C¹, C², are provided with the tapering recesses D, from the bottoms of 25 which project the knives D¹. The jaw C¹ is provided with the recess D² approximately semi-circular in cross section and tapering, and adapted to register with a corresponding recess D³ in the jaw C², 30 which recess has projecting from its bottom the knife D⁴, the edges of the knives D¹, D⁴, being arranged at an angle of approximately 45° with the two adjacent surfaces of the jaw members. The jaws C¹, C², are provided also with a triangular recess D⁵.

It will be evident that while we have shown in our drawings an operative device, still numerous changes might be made in the size, shape and arrangement of parts without departing materially from the spirit of our invention. We wish, therefore, that our drawings be considered as in a sense diagrammatic.

The use and operation of our invention

are as follows: The duplex wire to be stripped is seized between the jaws of the implement in such a manner that a plane passing between the two wires may include the cutting knives of the instrument. The handles are compressed and the jaws are drawn along the length of the wire, thus cutting the outer covering of the duplex. The single wire is then placed in the smaller recess and the operation is repeated, the single knife upon one of the edges acting to split the fiber and insulation whereby it can be conveniently pulled off. Any small particles of insulation or any foreign matter which may remain can be stripped off by drawing the wire through the small triangular recesses between the two jaws.

In our preferred form we show a knife arranged with its edge at an angle of 45° to the direction of motion of the wire. This is done in order that the cutting may not be done all at one point and adds greatly to the ease with which the wire may be stripped.

We claim:—

1. A wire stripper comprising a pair of rectangular recessed blocks and U shaped spring handle having one of said blocks at either end, recesses in each of said blocks registering one with the other and tapering knives upwardly projecting from the bottom of said recesses.

2. A wire stripper comprising a pair of rectangular recessed blocks and U-shaped handle having one of said blocks at either end, the recesses in each of said blocks being in register one with the other and tapering knives upwardly projecting from the bottom of said recesses.

THOMAS L. GREGSON.
JAMES I. PAYETTE.
